UNITED STATES PATENT OFFICE.

WILLIAM E. O'BRIEN AND EDWARD J. QUINN, OF KENOSHA, WISCONSIN.

RAILROAD-TIE.

1,066,520.

Specification of Letters Patent.

Patented July 8, 1913.

Application filed October 2, 1912. Serial No. 723,494.

To all whom it may concern:

Be it known that we, WILLIAM E. O'BRIEN and EDWARD J. QUINN, both citizens of the United States, and residents of Kenosha, in 5 the county of Kenosha and State of Wisconsin, have invented a new and Improved Railroad-Tie, of which the following is a full, clear, and exact description.

This invention relates to reinforced concrete cross ties, and has reference more particularly to the class comprising a body formed by a plurality of longitudinal and transverse members embodied in concrete.

An object of the invention is to provide an 15 inexpensive tie, simple, strong and durable in construction, which will form a solid support for the rail and offer proper resistance to the variable stresses produced by the rolling stock and atmospheric conditions.

20 A further object of the invention is to provide a concrete reinforced tie adapted to receive a railway plate and lock, and rigidly maintain said plate with the rail on the surface of the tie.

25 A practical embodiment of the invention is disclosed in the structure illustrated in the accompanying drawings forming part of this specification, in which like characters of reference indicate corresponding parts in all 30 the views, and in which—

Figure 1 is a side elevation of an embodiment of our invention, partly in section, showing the reinforcing longitudinal and transverse members near the vertical surface 35 of the tie; Fig. 2 is a plan view of the same, also partly in section, showing the reinforcing bars near the horizontal surface of the tie; Fig. 3 is a cross section on the line 3—3 in Fig. 1; Fig. 4 is a cross section on 40 the line 4—4 in Fig. 1; and Fig. 5 is an elevation of a vertical supporting link.

Before proceeding to a more detailed description of our invention it will be understood that a cross section of the tie may be 45 of any desired shape.

Referring more particularly to the drawings, 10 are longitudinal parallel and horizontal bars, properly spaced, each diagonally opposite pair of these bars being supported 50 by the diagonal cross bars 11, provided with an eye 12 at each end, and in which the longitudinal bars 10 are secured. By means of these eyes 12 the bars 10 are clamped to the diagonally crossing bars 11. The vertically 55 opposite pair of longitudinal bars 10 are inclosed and clamped in vertical links 13,

placed midway between two consecutive diagonal crossing pair of bars 11, whereby a series of alternate diagonally crossing bars 11 and vertical links 13 is provided on the 60 longitudinal horizontal bars 10.

The concrete 14 embodying the body and forming the tie is provided on its upper surface and near each end with a recess 15, having two side surfaces 16 converging toward each other, and into which the lock of the supporting plate projects. Near the recess 15 two orifices 17 are provided, by means of which the rail supporting plate is fastened. The recesses 15 are prismaticoidal 70 in form and in longitudinal vertical section form a trapezoid, as can be easily seen in Fig. 2.

It is a well known fact that in a railroad bed there are always pockets formed under 75 the ties that must be due to atmospheric conditions, and also to different elements constituting the ballast that forms the bed, and to give to the tie sufficient elasticity to withstand these compound flexures produced 80 by the pockets and rolling stock the longitudinal bars 10 are intended. While the diagonally crossing bars will transmit the pressure produced by the weight of the rolling stock to all parts of the tie, the vertical 85 links 13 will increase the crushing resistance at the edges, and with the longitudinal and crossing bars form a homogeneously resisting body.

Having thus described our invention, 90 what we claim as new and desire to secure by Letters Patent is:—

1. A device of the class described, comprising a plurality of longitudinal parallel and horizontal bars, and an alternate plurality of crossing and vertical bars supporting 95 said longitudinal bars in a predetermined position, the whole embodied in concrete to form a tie.

2. A device of the class described, comprising a plurality of longitudinal parallel and horizontal bars forming a rectangle in cross section, substantially diagonal crossing bars having clamping means at each end and clamping each diagonally opposite longitudinal bar, and vertical links clamping each 105 pair of vertically disposed longitudinal bars, the whole embodied in concrete to form a tie.

3. A device of the class described, comprising a plurality of longitudinal parallel and horizontal bars forming a rectangle in cross section, alternately-disposed substan- 110

tially-diagonal crossing bars having clamping means at each end and clamping each diagonally opposite longitudinal bar, and vertical links clamping each pair of vertically-disposed longitudinal bars, the whole 5 embedded in concrete to form a tie.

In testimony whereof we, WILLIAM E. O'BRIEN and EDWARD J. QUINN, have signed

our names to this specification in the presence of two subscribing witnesses.

WILLIAM E. O'BRIEN.
EDWARD J. QUINN.
